LEROY G. ZIMMERMANN, OF MILWAUKEE, WISCONSIN

MANHOLE CONSTRUCTION

Application filed March 7, 1928. Serial No. 259,890.

This invention relates to improvements in manhole constructions.

It is the object of the invention to provide a manhole casing adapted for factory manufacture and assembly and standardized units in the location and to the required depth of manhole.

Further objects of the invention relate to a novel top section unit adapted to receive a standard cover, and to a floating cover ring mounted on such unit and provided with centering means whereby it need not be secured to the aforesaid top manhole unit and may be heaved by frost independently of such unit without disturbing the proper relation of the parts.

In the drawings—

Figure 1 is a side elevation in perspective of a device embodying this invention, fragments thereof being broken away;

Figure 2 is a detail view in vertical section of the upper end of a casing device embodying this invention;

Figure 3 is a detail in transverse section taken in the plane indicated in 3—3 in Fig. 1;

Figure 4 is a side elevation of the bottom of the device;

Figure 5 is a detail view in plan of a fragment of one of the steps;

Figure 6 is a view of the step in transverse vertical section;

Figure 7 is a plan view of the device shown in Fig. 1;

Figure 8 is a section in the plane indicated at 8—8 in Figure 1.

Like parts are identified by similar reference numerals throughout the several views.

Only three principal types of castings are used to construct manhole casings in accordance with this invention. The fact that the number is limited to three effects great economies in manufacture and enables production methods to be employed for the first time in this industry.

The base section 10 is provided upon two

diameters with downwardly opening notches in its opposite margins, as shown at 11 and 12. Notches 11 are semicircular and of relatively large dimensions to take pipe of the relative size indicated at 13. Notches 12 are relatively smaller to receive pipes 14 which are laterals or delivery pipes or may comprise the main. It is intended, however, that pipe 13 shall represent the trunk line sewer and pipe 14 the laterals.

Upon the base 10 are assembled the annular sections 15 in vertical series to any desired height. The base section 10 at each of the intermediate sections 15 is provided with a belled top flange 16 into which the bottom margin of the next succeeding section is receivable, the joint being filled with cement, as at 17. It is obvious that a completely tight casing will result.

At the top of the series of intermediate sections 15, I employ an upwardly tapering top section 21 which is so formed as to extend almost vertically at the side 22 and to have a pronouncedly inclined wall at 18. The vertical wall at 22 makes the ladder, herein-after to be described, more readily accessible. The cover ring 19 has wedge-shaped centering lugs 20 at intervals about its under surface, such lugs being so disposed as to fit about the open mouth of the top section 21 to position or center the finishing plate 19 with respect to the opening.

In order that branch pipes or laterals may be introduced at a variety of angles to the interior of the manhole casing at any desired elevation, it is preferred to provide each of the several intermediate sections 15 of the casing with potential openings through which the lateral drains may extend. To this end each such intermediate section is provided at 25 a plurality of points (preferably 4) with round areas 25 of reduced thickness, such areas being bounded by beads 26 of increased thickness. As a result of this construction, it is readily possible to hammer or chisel out

the cast iron area of reduced thickness thereby leaving an opening of a size to receive a lateral pipe. The fact that each section is provided with a number of such potential 5 openings and that there are a number of sections at differing levels makes it possible to bring in a lateral at practically any desired point without requiring the castings to be made specially for each particular installation.

To afford access conveniently to the bottom of the manhole, I prefer to provide steps and hand holds in the form of a ladder. To this end each of the intermediate sections 15 is 10 provided in its top interior wall with lugs 28 having downwardly tapering apertures to receive the correspondingly tapered pin portions 29 of the steps 30. The sections 15 will be so assembled that the lugs 28 thereof will 15 be in vertical alignment whereby a complete ladder may be formed by the simple expedient of inserting the several step elements into their respective lugs in superposed relation.

In constructing a manhole casing embodying this invention, the bottom section 10 is 20 laid upon the completed length of pipe 13 which extends therebeneath. The pipe will be received into the notches 11 and 12, according to the angular position of the manhole, and, as above indicated, is preferably 25 received into notches 11. The bottom section is thus so positioned as to straddle the pipe.

Concrete mix will now be poured around 30 the pipe within and about the bottom section 10 of the manhole casing. The concrete will fill the bottom of the excavation at least to a depth sufficient to reach the lower margin of the section 10. This will imbed approximately 35 half of the pipe 13 in the concrete foundation. Thereafter, at any subsequent time, the top of pipe 13 is broken in by a sledge or with a chisel to provide an opening 300 for communication between the interior of the manhole and the interior of the pipe.

The several sections 15 are now laid up, one upon another, the joints between them being cemented, as above indicated, and at the 40 proper point the top section 22 is set in place. In laying up the sections 15 the weakened areas will be broken out and lateral drains introduced as may be required. The excavation about the manhole casing is now filled 45 with earth and the finishing ring 19 is laid to cover the upper margin of the top 22 and to receive the manhole cover 32. One of the difficulties heretofore experienced in the use of top plates or finishing plates has been the 50 fact that they afforded a horizontal surface against which the surrounding earth could exert pressure in expanding or heaving under the influence of frost. With a top plate manufactured in accordance with this invention, no difficulty is experienced due to the

fact that the top plate is floating and self-centering so that when the earth again contracts, the top plate will settle back into a properly centered position at the upper margin of section 21 of the manhole casing.

It will be observed that the majority of the parts entering into the construction of this device are standardized. If varying sizes of trunk line sewer pipes must be accommodated beyond the provision made therefor in 70 any single base unit, it is possible at relatively small expense to provide an alternative base unit. Likewise if any single lateral is of an odd size which cannot be accommodated by the construction herein described, it is possible to take care of it at relatively 75 small expense by making a single special intermediate casting. It will be noted, however, that so far as oversized laterals are concerned it is possible if desired to divide the lateral and bring it into the manhole casing through two or more of the openings already 80 provided for.

It is possible, therefore, to manufacture cast 85 iron manhole casings by production methods at prices sufficiently low to compete with the inferior masonry constructions heretofore employed.

It will be understood, of course, that the 90 shape of such casings is not specifically material. Each unit entering into the casing will necessarily be annular in the sense that each unit will comprise a closed geometrical figure when viewed in plan, or in other words, will have a continuous peripheral wall. This 95 does not mean, however, that the casing must necessarily be round as illustrated although the round construction is to be preferred because of convenience and economy. Neither 100 is it essential that the individual sections should maintain the illustrated ratio of diameter to axial extent, but here again it is preferred that the sections should be relatively flat in order that they may not be too 105 weighty and difficult to manufacture and handle. The diameter is preferably relatively large to give the desired size of manhole, while the axial extent is small in order that the units may conveniently be assembled with small increments of change to any desired structural height in order to meet existing 110 requirements at the place of installation.

I claim:

1. In a device of the character described, the combination with a casing member having a well defined upper margin, of an overhanging finishing plate adapted to cap said margin subject to the heaving action of frost and provided with radially disposed, marginally beveled lugs projecting downwardly 115 from said plate about said margin and engaged therewith in the normal relation of said plate and member, said lugs being formed to center said plate with reference to said margin upon the occurrence of rela- 120 125 130

tive axial movement between said plate and margin.

2. In a manhole casing the combination with an upwardly tapering casing member and a cover ring to be supported therefrom, of a finishing plate overhanging the upper end of said tapering member and providing a surface for the support of said cover ring, said plate having radially disposed lugs normally supporting its overhanging portion from the tapering surface of said member and adapted to center said plate with respect to said member upon the occurrence of relative vertical movement with respect thereto.
